[57] CLAIM

The ornamental design for an architectural learning device, as shown and described.

DESCRIPTION

FIG. 1 is a perspective view of an architectural learning device showing our new design;
FIG. 2 is a top plan view thereof, with the board omitted;

FIG. 3 is a front elevational view thereof, as shown in FIG. 2;

FIG. 4 is right side elevational view thereof, as shown in FIG. 2; and

FIG. 5 is an exploded perspective view of the base and templates thereof shown separately for clarity of illustration.
